UNITED STATES PATENT OFFICE

LUIS NOVELLI, OF BAHIA BLANCA, ARGENTINE REPUBLIC

SYSTEM OF IGNITION FOR EXPLOSIVE MIXTURES

Application filed August 7, 1929. Serial No. 384,220.

My present invention relates to a novel system of ignition of explosive mixtures, and has for its object to provide a possibility for employing any kind of fuel such as, fuel oil, 5 gas oil, kerosene, naphtha, benzine, alcohol, etc., thereby providing for a great economy as regards expenses of operation, and an improved operation of the motor.

In order that the invention may be better understood, same has been illustrated on the appended drawing showing a sectional view of the unit.

The construction of the present device is very simple and the same comprises a pump 15 for the fuel spray which pump causes the fuel to pass through a wire heated by an electrical current when passing into the cylinder. The said wire is connected to any source of electrical current, in any adequate 20 or approved manner.

In the said drawing, 1 denotes the ignition wire, 2 is the piston head of the motor, 3 indicates the piston segments or rings; 4 is the fuel spray nozzle, 5 being the valve thereof; 23 6 is the electric battery or current supply; 7 is the terminal for the filament; 8 is a lever for opening the nozzle valve; 9 is the fuel pipe; 10 denotes the cylinder of the motor; 11 is a cooling chamber; 12 is the gudgeon pin; 13 is the fuel pump which adjusts automatically the pressure within the pipe 23 9 and chamber 24. 14 is a spring adjusting the pressure degree of the fuel; 15 represents a fuel tank; 16 is a cam actuating the pump lever; 17 is a lever for actuation of the fuel pump; 18 is the adjusting screw thereon; 19 is the connecting rod to the piston; 20 is the second terminal of the ignition wire; 21 is a terminal for battery; 22 is the switch for 40 the ignition wire circuit; 23 is a cam actuating the valve lever of the spray nozzle; 24 is the hot fuel chamber; 25 represents a heating filament for the fuel; 26 is a terminal for the fuel heating filament; 27 is an insulated terminal carrying the current to the heating filament for the fuel; 28 is a switch for the circuit for the fuel heating filament; 29 is a current adjusting resistance on the filament, in order to adjust the temperature 45 of the fuel.

The operation of the device is as follows:—

The filament 1 is made incandescent by means of an electric current obtained through any system, for example, by means of an accumulator battery 6 as shown in the drawing. 55 The electric circuit is closed by means of the switch 22 and the current passes from the positive pole of the battery, through terminal 7 which leads the current to one point of the filament, the other point leading to the motor mass by means of terminal 20. The negative pole of the accumulator leads directly to the motor mass by means of terminal 21, whereby the electric circuit is closed.

The fuel is compressed within pipe 9 by 65 means of the pressure adjusting pump 13 when the piston travels upwards during its compression stroke compressing air. At the completion of its stroke, that is, at the completion 70 of the compression, the cam 23 lifts the valve lever of the spray nozzle thus permitting the fuel to pass (the fuel being already heated through filament 25) on. As the fuel is under a pressure greater than that existing 75 within the cylinder, it enters the spray nozzle 4 and projects speedily on to the incandescent filament whereby the explosion is produced and the motor is started. With this arrangement, a motor may work with any fuel, such as, fuel oil, gas oil, kerosene, naphtha, benzine, alcohol, etc.

Obviously, when carrying this invention into practice, there may be made different modifications as construction is concerned, but all such modifications should not exceed 85 the fundamental principles of the invention as clearly set forth in the appended claims.

Having thus fully described and ascertained the nature of my said invention and the manner in which the same is to be performed what I claim as of my exclusive proprietorship and invention is:—

1. The combination of a combustion engine, a pressure fuel supply having a conduit leading directly to a combustion chamber of the engine; an electric heating element within and coextensive with the conduit; and an ignition element within the chamber confronting the inlet thereto from the conduit. 95
2. The combination of a combustion en- 100

gine, a pressure fuel supply having a conduit leading directly to a combustion chamber of the engine; an electric heating element within and coextensive with the conduit; an ignition element within the chamber confronting the inlet thereto from the conduit; and timed means regulating the admission of fuel to the chamber incident with the compression period of the engine.

10 3. The combination of a combustion engine, a pressure fuel supply having a conduit leading directly to a combustion chamber of the engine; an electric heating element within and coextensive with the conduit; an ignition element within the chamber confronting the inlet thereto from the conduit; timed means regulating the admission of fuel to the chamber incident with the compression period of the engine; and means for regulating the heating element and ignition element independently or together.

15 4. The combination of an internal combustion engine cylinder and piston therein, a fuel spray inlet nozzle leading into the cylinder; a pressure fuel supply having an elongated delivery tube connected with the nozzle; an electric heating element within and coextensive with the tube; timed mechanism having a valve within the nozzle and opened on the compression stroke of the piston; and an ignition device confronting the nozzle and coactive with the heating element or active independently thereof.

In testimony whereof I affix my signature.

35 LUIS NOVELLI.
